UNITED STATES PATENT OFFICE.

WILLIAM B. FAGAN, OF WAUWATOSA, WISCONSIN, ASSIGNOR TO UNITED SHOE MACHINERY CORPORATION, OF PATERSON, NEW JERSEY, A CORPORATION OF NEW JERSEY.

EDGE-TRIMMING MACHINE.

Application filed September 3, 1927. Serial No. 217,336.

This invention relates to machines for trimming the edges of the soles of shoes and more particularly to trimming the shank portions of the soles.

The usual procedure in trimming the edge of a sole is to trim the forepart with a rotary toothed cutter having one profile, and to trim the edges of the shank portion as far as possible to the rear with another rotary toothed cutter having a different profile better suited to shank trimming. It is necessary, however, to end the shank trimming some distance in front of the breast of the heel to avoid damage to the latter, since if the trimming with a rotary cutter were continued all the way to the breast of the heel it would be impossible to avoid nicking the heel. Consequently, when the shank trimming has progressed toward the heel to a point where it is no longer safe to continue the trimming with a rotary cutter, the shoe is removed from the cutter. This leaves short untrimmed portions on the shank that project laterally beyond the sides of the heel and that require trimming by some other kind of a device so that the edges of the shank, where they meet the heel, will be flush with the sides of the latter. This final trimming of the shank is commonly termed "jointing," and it is particularly with this jointing problem that the present invention is concerned.

In operating on a shoe, the heel of which has a breast face that is substantially perpendicular to the plane of the shank where the heel and shank meet, the jointing operation may be satisfactorily performed with jointing machines heretofore supplied to the trade, but such jointing machines are not so well adapted to produce satisfactory joints in shoes fitted with Louis heels, the breasts of which curve sharply and merge into the bottom surfaces of the shanks.

Another problem is encountered in jointing women's McKay shoes. In shoes of this type the margin of the outsole is channeled to provide a channel flap under which the outsole stitches are concealed when the shoe is finished, the flap being laid back during the stitching operation and subsequently returned to its normal position and cemented to the margin of the body of the sole. Moreover, in women's turn shoes, as well as in women's shoes of the McKay type, the mar-

gins of the shank of the outsole are usually reduced to a thin edge to render the shank light in appearance as well as in fact. Consequently when the thickness of the margin is reduced, considerable stiffness is sacrificed, and the difficulty in trimming the edge is increased, since a thin and relatively pliant edge bends more or less when pressure is brought to bear against it. This condition presents a particularly serious problem in McKay shoes, since the channel flap is dependent for its support upon adhesion to the body of the sole, and when the latter has been rendered comparatively pliant at its margins in consequence of its reduction in thickness, lateral pressure against the edges of these two elements tends to crumple them and sometimes actually ruptures the bond of cement between them.

In view of the problems herein above set forth an object of the present invention is to provide improved apparatus adapted to perform a satisfactory jointing operation on shoes the heels of which have breast faces otherwise than substantially perpendicular to the plane of the shank portions of the soles. To this end a feature of the invention consists in a machine comprising a reciprocatory tool holder and a tool carried thereby and having two angularly related meeting surfaces one of which is arranged to bear against the marginal portion of the bottom surface of the sole while the other bears against the edge of the sole, the tool also having a series of kerfs intersecting the face that bears against the edge of the sole and dividing this face into teeth adapted to trim the edge of the sole with a scraping action. The said face that is arranged to bear against the bottom surface of the sole is preferably smooth and functions not only as a guide to maintain the edge of the sole in the desired relation to the teeth but also braces the margin and thereby furnishes temporary rigidity to the material upon which the teeth are operating.

When the above described tool is used to perform a jointing operation on a sole the shank of which has been reduced in thickness at its margins the bracing effect referred to above is particularly advantageous, but it is even more so when operating upon a shoe of the McKay type in that the smooth face that bears against the bottom of the sole main-

tains pressure of the channel flap against the marginal portion of the body of the sole. In this respect the described tool not only prevents distortion of the relatively thin margin of the sole but it also prevents separation of the channel flap from the body of the sole.

Referring to the drawings,

Fig. 1 is a front elevation of a portion of a machine adapted to perform a jointing operation, said machine being equipped with a jointing tool embodying the novel features of the present invention;

Fig. 2 is a side elevation of said tool and a portion of a reciprocatory holder by which it is supported and operated, the outline of a shoe being represented in dotted lines;

Fig. 3 is a view similar to Fig. 2 but on a larger scale, and represents the shoe in cross-section, the plane of the section intersecting the shank of the shoe close to the breast of the heel;

Fig. 4 is a perspective view including an outsole and a Louis heel but omitting the upper or body of the shoe to illustrate the condition of the sole that requires the so-called jointing operation;

Fig. 5 is a front elevation of the jointing tool illustrated in Figs. 1, 2 and 3;

Fig. 6 represents a portion of said tool on a larger scale;

Fig. 7 represents the said tool as viewed in the direction indicated by an arrow in Fig. 3; and

Fig. 8 is a perspective view of said tool as viewed from one side.

The general organization of the mechanism illustrated in Fig. 1 is similar to that of a well-known type of edge-setting machine which has proved to be satisfactory for performing a jointing operation when equipped with a tool embodying the novel features of the present invention. Said machine, so far as it is here shown, comprises a frame 10 in which a high-speed rotary shaft 12 is journaled. A wrist pin 14 projecting from one end of said shaft operates a connecting rod 16 by which a lever 18 is oscillated about a center indicated by a dotted circle 20. This lever is provided

50 with a reversible tool-holder 22 from which two cylindrical studs 24 project, but for the purpose of the present invention either of the studs 24 is sufficient to hold the jointing tool 26 hereinafter described.

55 The tool 26 is made of steel and is hardened to give it durability. It is, in some respects, similar to tools commonly provided for edge-setting but differs from edge-setting tools in that it is provided with a series

60 of teeth 28 each adapted to trim, with a scraping action, some of the surplus material from the edge of the sole of a shoe. The tool 26 is provided with a cylindrical socket 30 (Fig. 5) adapted to receive a stud 24

65 projecting from the holder 22. A notch 32

(Figs. 7 and 8) is formed in one end of the tool to receive a key or pin 34 projecting from the holder 22, the tool being thus prevented from turning relatively to the stud 24. The holder 22 is provided with a spring 70 detent 36, and the tool 26 is provided with a notch or depression 38 adapted to receive said detent, so that when the tool is forced home relatively to the holder 22 it will be maintained by the detent in interlocked relation with the stud 24 and the pin 34 and still be capable of being detached by a slight pull away from the holder.

The tool 26 is formed with a smooth surface 40 arranged to bear against the bottom surface of the shank 42 of the sole of a shoe, this surface 40 being preferably convex as shown in Figs. 7 and 8. The tool is also provided with a shoulder 44 (Figs. 2 and 3) which projects from the surface 40 substantially at right angles to the latter to engage the edge of the sole. The shoulder 44 is also preferably convex, as illustrated in Figs. 5 and 6, although in these figures it is divided into the teeth 28 by a series of parallel saw kerfs 46 the bottoms of which are flush with the surface 40 (Figs. 7 and 8). Thus, each tooth 28, where a kerf 46 intersects the shoulder 44, is provided with a sharp acute-angular edge 48. Some of the edges 48 are arranged to trim or scrape the edge of the sole when the tool moves transversely of the kerfs in one direction and the others are arranged to have the same effect when the tool moves in the opposite direction. The double pointed arrow in Fig. 6 indicates the directions and approximately the amplitude of the motions imparted to the tool by the lever 18, these motions being curvilinear by reason of the angular motion of the lever about the center 20.

Fig. 4 is not intended to represent the actual condition of a shoe in process of manufacture, since the upper or body of the shoe is omitted therefrom, and it will, therefore, be understood that in actual practice the sole and heel are both attached to a shoe, and that the upper is omitted from the figure merely for the sake of showing to better advantage the untrimmed projecting portions 50, 50 remaining on the shank 42 as a result of partially trimming the edges of the shank with a rotary cutter according to common practice. The purpose of the tool 26 is to trim off the untrimmed portions 50, 50 back to the dotted lines 52 so that the edges of the shank will merge into, and be flush with, the sides 54 of the heel.

In women's turn shoes the margin of the sole is considerably reduced in thickness throughout, whereas in women's McKay shoes it is common practice to reduce the thickness of the margins of the shank of the outsole to produce the appearance of light-

ness. Consequently, when the partially trimmed shank of either of these types of sole is presented to the jointing tool 26, the pressure against the edge of the shank tends to bend or crumple the edge. Moreover, in shoes of the McKay type, as shown in Fig. 3, the margin of the outsole is further weakened by cutting it to provide a channel to receive the stitches 56 that connect the outsole, the insole 58 and the upper 60. Although the channel flap 62 is cemented to the thin marginal portion 64 of the shank before the edge is trimmed, these parts, if bent or crumpled, would burst their bond of adhesion. Still, whatever the margin of the shank lacks of stiffness in consequence of being relatively thin where the surplus material lies, it is reinforced by the surface 40 of the tool 26 while the latter is operating. This surface, when held against the bottom of the margin of the shank, braces the latter against bending and crumpling, its area of contact with the margin being contiguous to the point at which the teeth 28 press against the edge of the shank.

In addition to bracing the margin of the shank, the surface 40, when bearing against the channel flap 62 of a McKay sole, presses the flap against the margin 64. This not only prevents separation of the flap and the margin 64 but also closes any crack that may have been left between them. At the same time the rubbing action of the surface 40, due to vibration of the tool, smooths the channel flap and causes closer adhesion of the latter to the margin 64.

The operation of cutting the kerfs 46 produces burrs on the operating edges 48, and these burrs increase the trimming effectiveness of the tool 26. Thereafter, when the edges 48 become dull from use, they may be readily sharpened and new burrs formed by filing the sides of the teeth with a thin flat file inserted in the kerfs.

Having described my invention, what I claim as new and desire to secure by Letters Patent of the United States is:—

1. A machine for operating on the edge of the sole of a shoe, comprising a reciprocating tool having two angularly related meeting faces one of which is arranged to bear against the marginal portion of the bottom surface of the sole while the other bears against the edge of the sole, and having a series of kerfs intersecting said other face and dividing the latter into teeth adapted to trim said edge with a scraping action, and

means arranged to reciprocate said tool transversely of said kerfs.

2. A tool for performing a jointing operation on the shank portion of the sole of a shoe, having a smooth integral surface arranged to bear against the marginal portion of the bottom surface of the shank, a shoulder arranged to bear against the edge of the shank, and a series of kerfs intersecting said shoulder and dividing it into teeth adapted to trim off the surplus material with a scraping action. 60

3. A tool for performing a jointing operation on the shank portion of the sole of a shoe, having a smooth and slightly convex surface arranged to bear against the marginal portion of the bottom surface of the shank, a shoulder projecting from said smooth surface in substantially perpendicular relation thereto, said shoulder having a series of parallel kerfs by which it is divided into teeth, the bottoms of said kerfs being substantially flush with said smooth 75 surface, and said teeth being arranged to trim surplus material from the edge of the shank with a scraping action when the tool is reciprocated transversely of said kerfs. 70

4. A tool for performing a jointing operation on the shank portion of the sole of a shoe, having a slightly convex shoulder adapted to engage the edge of the shank, a series of parallel saw-kerfs intersecting the work-engaging surface of said shoulder and dividing the latter into teeth adapted to trim the surplus material from said edge with a scraping action when the tool is reciprocated transversely of said kerfs, and a smooth portion projecting from the bases of said teeth 95 to engage the marginal portion of the bottom of the shank and thereby brace said marginal portion against crumpling. 90

5. A tool for performing a jointing operation on the shank portion of the sole of a shoe, having a smooth surface arranged to bear against the bottom of the marginal portion of the shank, and a convex shoulder projecting from said smooth surface to bear against the edge of the shank, said shoulder being intersected by a series of parallel kerfs dividing it into teeth and forming a series of acute-angular edges that stand up from said smooth surface to trim or scrape the edge of the shank when the tool is reciprocated transversely of said kerfs. 100

In testimony whereof I have signed my name to this specification.

WILLIAM B. FAGAN.
